G. A. WOOD.
TRAFFIC POST.
APPLICATION FILED SEPT. 22, 1920.

1,402,465.

Patented Jan. 3, 1922.

UNITED STATES PATENT OFFICE.

GEORGE A. WOOD, OF ELMIRA, NEW YORK.

TRAFFIC POST.

1,402,465.

Specification of Letters Patent. Patented Jan. 3, 1922.

Application filed September 22, 1920. Serial No. 412,011.

To all whom it may concern:

Be it known that I, GEORGE A. Wood, a citizen of the United States of America, residing at Elmira, in the county of Chemung 5 and State of New York, have invented certain new and useful Improvements in Traffic Posts, of which the following is a specification.

This invention relates to certain new and 10 useful improvements in traffic posts known in the art as "silent cops" and is especially designed for mounting at the intersection of crossing streets to indicate to the drivers of vehicles the proper course to pursue in passing 15 a street crossing.

A further object of the invention resides in the provision of a traffic post in the form of a sign post indicating to drivers of vehicles the proper direction of travel and 20 wherein the post includes a resilient mounting to cause the same to assume a perpendicular position and also to permit the knocking down of the same in any direction when engaged by a moving vehicle, thereby 25 preventing damage to the machine and insuring the restoration of the same to its proper engaging position.

With the above general objects in view and others that will appear as the nature of the 30 invention is better understood, the same consists in the novel form, combination and arrangement of parts hereinafter more fully described, shown in the accompanying drawing and claimed.

In the drawing, wherein like reference characters indicate corresponding parts throughout the several views,

Figure 1 is a vertical sectional view of a resiliently mounted traffic indicating post 40 constructed in accordance with the present invention,

Figure 2 is a horizontal sectional view taken on line II—II of Fig. 1,

Figure 3 is a fragmentary sectional view 45 of a modified form of the invention showing a prolate spheroid mounting base, and

Figure 4 is a horizontal sectional view taken on line IV—IV of Fig. 3.

Briefly described, the invention has for its 50 main object to provide a traffic indicating sign post adapted for positioning at the center of crossing streets, and other places to indicate to motorists, and drivers of other vehicles the correct direction of travel. The 55 post may have a metallic cylindrical cover-

ing, or the covering may be of a cushioning material such as leather or rubber, while the mounting base therefor extends downwardly into a cylindrical housing with a coil spring 60 engaging the lower end thereof to cause the post normally to assume a perpendicular position. The base of the post is of hemispherical construction so that the post is capable of being knocked down in any direction when struck by a moving vehicle and subsequently restored to its perpendicular position by the spring engaging the base of the post within the housing.

Referring more in detail to the accompanying drawing, there is illustrated a traffic 70 indicating sign post mounted in a cylindrical housing H sunk within the ground as indicated by section with the upper end thereof terminating adjacent the line of the street.

The indicating post includes a mounting 75 base E of substantially hemispherical construction entirely received within the open upper end of the housing H when in its perpendicular position and is provided with a centrally threaded socket for the reception of a vertical rod B threaded therein at its lower end.

An annular shoulder is carried by the upper end of the mounting base E and is of sufficient diameter to be received in the annular seat H' in the upper 80 end of the housing H to hold the mounting base at the upper end of the housing.

A tubular covering C encloses the rod B and may be of any desirable material, either metal, rubber, leather, etc., and to hold the tubular covering C in position on the rod with the lower end thereof engaging the mounting base E, there is provided a screw cap 85

A threaded on the upper end of the rod B engaging the tubular covering and clamping the same between the cap and the mounting base, thereby locking the disk to the mounting base E and also securing the tubular covering on the rod.

The resilient mounting for the base E includes a coil 90 spring G secured at its upper end to the eye-bolt F depending from the lower side of the mounting base E while the lower end of the spring engages the cross bar I extending transversely of the lower end of the 95 housing H, thus maintaining the post above the street line in a normally perpendicular position as indicated.

If desired, any notation whatever may be 100 painted or otherwise impressed on the tubu- 110

lar covering C to indicate the direction of travel of vehicles. In operation, the post is in its normally vertical position as indicated, but should a vehicle contact the same the post will be knocked down in any direction by the vehicle against the tension of the spring G and after such engagement the spring will return the post to its normal perpendicular position, thereby eliminating serious damage to the vehicle and immediately presenting the post for its proper indicating function. As the mounting base E is of substantially hemispherical construction and the shoulder D is of annular formation the post will be permitted to be knocked down in any direction opposed to the force of a striking vehicle.

The modified form of the invention shown in Figs. 3 and 4 embodies the substitution of a prolate spheroid E' for the hemispherical mounting base shown in Fig. 1, thereby providing a longer body portion of the mounting base extending into the housing H. Also, in this form, the annular shoulder D' rests upon the upper edge of the housing H.

While the forms of the invention herein

shown and described are believed to be preferable, it is nevertheless to be understood that minor changes may be made therein without departing from the spirit and scope of the invention as claimed.

What is claimed as new is:—

A traffic indicator of the type described comprising a tubular housing, an indicator post, including a mounting base disposed within the upper end of the housing, said mounting base being of substantially hemispherical form and having an annular shoulder superposed thereon for engaging upon the upper end of said tubular housing, a rod threaded at its opposite ends having one end threaded into the base, a tubular cover for said rod being supported at its lower end upon the substantially flat upper surface of the hemispherical base and rigidly engaged upon said rod by a nut threaded upon the upper end of the rod and contacting with the upper end of said tubular cover, and a resilient connection between the mounting base and housing.

In testimony whereof I affix my signature.

GEORGE A. WOOD.
